Primary Examiner — Darlington Ly

(57) **CLAIM**

The ornamental design for a three-wheeled vehicle, as shown and described.

DESCRIPTION

FIG. 1 is a left-front perspective view of a three-wheeled vehicle showing my new design;

FIG. 2 is a right-front perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a left-rear perspective view thereof;

FIG. 8 is a right-rear perspective view thereof;

FIG. 9 is an enlarged view of a left front wheel well thereof;

FIG. 10 is an enlarged view of a rear quarter and B-pillar thereof;

FIG. 11 is an enlarged view of a side body portion thereof; and,

FIG. 12 is an enlarged view of a rear body section thereof.
